FABRIC TREATMENT

Paul M. Cole, Wilmington, Del., assignor to E. I. du Pont de Nemours and Company, Wilmington, Del., a corporation of Delaware

Application May 27, 1954, Serial No. 432,824

5 Claims. (Cl. 8—152)

This invention relates to treatment of textile fabric, particularly placement of fabric onto a rotary carrier and subsequent removal therefrom.

Supporting of fabric in open width is conductive to satisfactory uniformity of dyeing and finishing, but economy in such textile operations is dependent upon efficacious treatment of considerable quantities of fabric. Cole patent application Serial No. 347,263, filed April 7, 1953, describes such treatment upon rotary carriers that support the fabric substantially tension-free and advance it in a star-like pattern. The mentioned patent application illustrates the hitherto normal loading method for such a carrier, which may be termed "parallel" loading; in that method, each of a plurality of lengths of fabric makes a complete wrap around the rotor (forming the star pattern, as viewed along the axis of the rotor). The carrier has supporting bars spaced in an outer circle for the fabric to pass over and similar supporting bars spaced in an inner circle for the fabric to pass under; the fabric normally passes over an outer bar, under an inner bar, over the next outer bar, and so on around the carrier, assuming the zigzag configuration of the "arms" of a star. To facilitate loading and unloading, the inner bars customarily are removable, being inserted in slotted guides extending from the periphery of the carrier. While the length of a complete wrap may be made less than the maximum for any particular carrier of this type by omitting or by-passing some of the bars, unavoidable variation in the lengths of pieces of fabric to be loaded complicates the procedure: pieces too long for a single wrap must be cut, and pieces too short must be furnished with a leader to complete the wrap. Conventional weaving operations are not adapted to close control on the length of fabric produced thereby.

A primary object of the present invention is replacement of parallel loading of a rotary dyeing or finishing machine by series loading. Another object is preforming of fabric in a holdup system into a continuous multi-layered loop having the desired length of a single wrap for a rotary carrier and gradual withdrawal of the loop of fabric therefrom during loading of the carrier. An object is placement of a length of fabric longer than a single wrap onto a rotary carrier in star-shaped pattern without necessity for cutting or piecing of the fabric irrespective of the excess in length. Other objects of this invention will be apparent from the following description and the accompanying diagrams.

Figure 1 is a schematic side view of removal of fabric from a source of supply onto a wrap-length holdup system. Figure 2 is a similar view of holdup means and a rotary carrier at an early stage in the loading of the fabric of Figure 1. Figure 3 is a view similar to that of Figure 2 but showing the loading nearly completed.

In general, the objects of the present invention are accomplished by unwinding fabric from a supply source onto a holdup system, in which the length of one complete turn is equivalent to the length of one wrap about a rotary carrier, superimposing in a continuous spiral

2

successive wrap-length layers of fabric in substantially non-slipping contact with one another until the supply is discontinued; a loop of the multiple-layered wrap so formed is slipped bodily over the end of a rotary carrier

5 and onto fabric-supporting members thereof, whereupon the rest of the fabric is fed gradually from the holdup system onto the carrier until all the fabric leaves the holdup system and rests as a star-shaped wrap about the carrier. Here terms referring to the configuration of a

10 star comprehend not only the familiar five- and six-pointed star patterns consisting, respectively, of ten and twelve straight zigzag lines or "arms" (connecting points located alternately on a circle inscribed in the star and a circle circumscribing the star) but also multi-pointed

15 figures generally that present a closed zigzagging pattern about a central point, regardless of moderate curvature or length inequality of the various arms and any skewing of the pattern about the center, as often may be desirable. The invention is illustrated with particular reference to a rotary carrier having slotted guides to receive removable inner bars from locations at the periphery of the carrier (between the outer bars with which the inner bars cooperate in supporting a wrap of fabric in the configuration of a star).

20 25 As used here, "holdup" signifies temporary storage of all or part of a fabric load for the carrier. While a holdup system could be designed to carry the fabric extended at wrap length, such an arrangement would be unnecessarily voluminous; it is convenient for the system to provide a concentrated storage section where a

30 considerable amount of fabric may be confined to a small volume. Figure 1 shows a preferred embodiment in which fabric 1 (represented by a solid line) from supply beam or mandrel 2 passes over bar 3, about roll 4, through tacking means 5, about expander roll 6, under bar 7, also under bow bar 8, about removable roll 9, in contact with feed roll 10, through the nip of plaiter drive roll 11 and removable idler roll 12, and onto scray 13, in which it accumulates in folds. From the scray the fabric passes about bar 14, over expander roll 15 and into contact with the body of the fabric under bar 7. An alternative path (1') appears in dashed lines at the right, where the fabric passes in folds into truck 16, with the plaiter similarly shown.

35 40 45 The sequence of steps by which the fabric is preformed into a multiple-layer of wrap length, as shown in Figure 1, is comparatively simple. At the beginning of the operation, the end of the fabric from the supply mandrel is fed through the system manually; as soon as the length required for a complete wrap on the treating rotor has been unwound, the end of the fabric is secured or tacked to the body of the fabric to form a loop of that length, whereupon the drive rolls feed the fabric repeatedly about the circuit until the entire load of fabric is unwound.

50 55 It is desirable to ensure substantially non-slipping contact between adjacent layers of the fabric in order to maintain each layer in the loop at the desired length, both in the holdup system and later on the carrier. Sewing or stapling at the ends and wetting of the intervening fabric (or intermittent fastening of the multiple selvages) suffices to maintain all the layers of fabric at wrap length. The operator in charge of the preforming operation usually performs the fastening of the ends manually, but the tacking means may include one or more machines to accomplish this besides comprising a dip tank or other means for tacking together the layers in the resulting loop. The film of water placed between adjacent layers of fabric on its passage through ordinary wetting means

60 65 70 normally is highly effective in holding them together, and sewing or other fastening at the selvages or across the body of the fabric is unnecessary.

As the last wrap-length portion of fabric unwinds from the supply source it is convenient for the operator to move the plaister rolls from the original position over the scray to the alternative position shown in Figure 1 (by dotted lines) and to set the rolls swinging in the arc indicated by a double arrow, so as to plait or fold the fabric into the truck. Of course, to permit this he frees the bars and rolls encircled by the loop of fabric, including finally rolls 9 and 12 if the plaister is not to be used in the step of loading the fabric on the carrier. Thus, the entire wrap-length loop may be stored temporarily in the truck and moved about therein if desired.

Access to the end of the rotary carrier upon which the fabric is to be loaded and treated may be facilitated by cantilevering or counter-weighting it sufficiently to free one end from any further external support. Or this may be provided in any number of ways by means of a removable external support at that end, as is readily apparent. When a removable support is used, there should be sufficient space between it and the end of the rotor to permit convenient location of the fabric next to the end before replacement and during operation of the support. When the end is raised or supported sufficiently, the fabric is slipped onto the body of the rotor in open width. Figure 2 shows the stage of the loading operation shortly thereafter, using a rotary carrier adapted to support the fabric in the pattern of a star and furnished with guides extending from the periphery of the carrier to locations near the axis to hold the inner fabric-supporting bars. The carrier, which appears in section perpendicular to axle 35, comprises flange 33 (an opposing flange, mirror image of 33, is not visible in this sectional view) with outer bars 32 in place, while bars 34 are being fed from track 37 above into guide slots 36. Each guide slot is furnished with a pin or other means (not shown) to confine the end of a bar at the innermost end thereof so as to constitute an inner support for the fabric. Truck 26, which may be the same as truck 16 of Figure 1 (appearing turned end-for-end), is juxtaposed to the carrier. Multiple wrap 31 of fabric rests mainly in the truck, but enough has been removed to surround the carrier and elements of the feeding or winding means. Plaister rolls 21 and 22, which are not required in the step of loading the fabric onto the rotary carrier appear to one side above the truck. In the path of the fabric represented by the solid line are roll 23 centered above the truck and idler roll 19 and drive roll 20, which is driven by external means (not shown). Rack 37 carries a supply of bars 34 above and to the right of the carrier. The first inner bar 34' is halfway down in the closest guide slot 36' with a festoon of fabric held thereby.

An operator sets the carrier and the feeding rolls into motion, which may be either continuous or intermittent, to accomplish the loading step. The relative rates may be synchronized mechanically to ensure festooning of the proper length of the fabric loop between each pair of outer bars. Release of an inner bar from the rack into each guide slot is easily accomplished manually or mechanically. The operator also ensures that each inner bar is held securely at the innermost end of its slot to prevent it from falling out at the lower half-cycle of carrier rotation.

As successive inner bars fall into place, the amount of fabric in the truck lessens, and near the end of the loading period the terminal portion of the fabric loop is freed by removal or swinging aside of roll 19 and roll 23. This instant is represented in Figure 3. The rest of the fabric is just long enough to be taken up on the rotary carrier by insertion of the last inner bars, whereupon fluid treatment of the fabric may begin. Of course, as in pressure dyeing, the treatment may require placement of the carrier in a suitable housing. In the absence of the truck the loading could proceed directly from the

scray of Figure 1, or other holdup means could be employed to practice the described loading of the wrap-length loop of fabric.

Unloading of the fabric is substantially the reverse of loading and may be visualized readily without the aid of further diagrams. Manual removal of a couple of the inner bars from the carrier permits replacement of part of the fabric loop onto feeding means of the holdup system, after which the bars removed in Figure 3 and the plaister rolls are placed in the fabric path (including the dashed-line alternative) and the drive rolls set rotating in the opposite direction from before. During this step the fabric itself is tensioned sufficiently by the winding to lift the inner bars, which are released by the operator from their positions near the axis immediately beforehand to permit their removal. The fabric is plaited or folded into the truck by the swinging plaister rolls. When all but one of the inner bars are returned to the supply rack, the situation reverts to that shown in Figure 2 (including the dashed-line alternative path) except that all the directions of travel are reversed. After removal of the last inner bar, the fabric is slipped off the end of the carrier, and all the excess placed in the truck. The outer end of the fabric is freed from the other layers and is fastened to a windup roll onto which the entire fabric then is rewound. If a sufficiently light-weight thread has been used for tacking the ends or intermediate portions of the fabric, the winding force will break it easily and the remaining bits of thread may be brushed off, or a cutter may be used between the separating layers of fabric to part the thread. Other fasteners may be removed by the operator.

The method of loading and unloading here described has many advantages in addition to its ready accommodation of diverse lengths of fabric. Two or more similar holdup systems may be employed to permit immediate unloading and loading of the carrier without delay for filling and emptying of the scray or other members of the system. The relatively portable elements of the holdup system and related elements need not be located nearby throughout the operations but may be moved about, as may be convenient, except during the brief period of transfer of fabric to or from the carrier itself, which is shorter with the multiple-layered or series-wound wrap than with the separate lengths of fabric used in the previous parallel method. According to this invention, economical utilization of the carrier is increased further and both fabric waste and excessive labor formerly incurred in cutting and piecing of the lengths of fabric are eliminated. Many other advantages of the practice of this invention will come readily to mind.

What is claimed:

1. In the process of loading fabric onto a rotary carrier adapted to support a wrap of fabric in the pattern of a star, as viewed along the axis of the carrier, the improvement comprising first preforming the entire fabric load into a continuous multilayered loop having the desired length of a complete star-like wrap about the carrier, then slipping the loop about the carrier by passing it over the end thereof and subsequently supporting it thereon in a zig-zag star-like pattern.
2. The process improvement of claim 1 in which the preformed loop of fabric is withdrawn gradually from a nearby holdup system onto the carrier during the step of supporting the fabric thereon in the star pattern.
3. Process of loading an endless loop of fabric onto a rotary carrier adapted to support the fabric about outer and inner bars in the pattern of a star, as viewed along the axis of the carrier, comprising slipping a portion of the loop over the end of the carrier to rest upon the outer supporting bars thereof and then inserting inner bars successively in the carrier to festoon the fabric between adjacent outer bars and thereby withdraw the rest of the loop gradually from a nearby holdup system until

all the bars are in place and the complete loop of fabric is removed from the holdup system and supported as a star-shaped wrap upon the carrier.

4. Process of loading fabric onto a rotary carrier adapted to support fabric about outer and inner bars successively in the pattern of a star, as viewed along the axis of the carrier, comprising unwinding fabric from a supply source, passing the end of the fabric through a holdup system until the length of fabric therein equals the desired length of one wrap about the carrier, fastening the end to the fabric body to make an endless loop of that length, passing the loop of fabric unidirectionally through the holdup system and tacking the fabric newly unwound from the source to the fabric in the loop until the desired total quantity of fabric has accumulated as multiple layers in the loop, passing a portion of the loop over the end of the rotary carrier to rest in open width upon the outer supporting bars thereof, inserting inner

bars successively in the carrier to festoon the fabric between the outer bars at the expense of the fabric content in the holdup system, whereupon with insertion of all the inner bars in the carrier no more fabric remains in the holdup system and the multilayered loop of fabric forms a complete star-shaped wrap upon the carrier.

5. In combination with a rotary carrier adapted to support a wrap of fabric in a zig-zag star-shaped pattern, as viewed along the carrier axis, holdup means for pre-forming fabric into a single endless wrap-length multi-layer loop and feeding means for transferring the fabric between the holdup means and the carrier and forming a zig-zag star-shaped pattern on the carrier.
